CLAIM

The ornamental design for scoreboard in the form of a baseball, as shown and described.

DESCRIPTION

FIG. 1 is a front view of a scoreboard in the form of a baseball showing our new design;

FIG. 2 is a side view thereof.

FIG. 3 is a front view of a second embodiment of a scoreboard in the form of a baseball; and,

FIG. 4 is a side view of FIG. 3.

The broken lines showing the environment is for illustrative purpose only and form no part of the claimed design.
